United States Patent Office.

SOCRATES SCHOLFIELD, OF PROVIDENCE, RHODE ISLAND.

Letters Patent No. 91,970, dated June 29, 1869.

IMPROVEMENT IN BRAIDING-MACHINES.

The Schedule referred to in these Letters Patent and making part of the same.

To all whom it may concern:

Be it known that I, SOCRATES SCHOLFIELD, of Providence, in the county of Providence, and the State of Rhode Island, have invented an Improvement in Braiding-Machines; and do hereby declare that the following is a full and exact description thereof, reference being had to the accompanying drawing, making a part of this specification.

The nature of my invention consists in certain improvements in the stop-motion and carriers, whereby a high rate of speed may be secured with practical economy.

To enable those skilled in the art to make and use my invention, I will describe its construction and operation.

A, in Figure 1, represents a top view of the grooved plate of the machine.

B is the stop-rim, having a limited movement in the arc of a circle.

b b b are projections, against which the tension-weight is to strike, when the thread breaks.

C is a spring, operating upon inclined, or cam-surfaces, to bring the stop-rim back to a central position, whenever moved in either direction.

Instead of arranging this spring to operate upon the inclined surfaces, as shown, it may be secured immediately to the stop-rim, in any convenient manner, so as to always bring it back to the proper place.

D is the handle, to be moved when the machine is to be started.

The spring L, attached to the stop-rim, catches in the notch d on the handle D, thus holding the clutch in gear, until the stop-rim is moved so as to throw the spring L out of the notch d, either the sides of the notch, or edges of the spring being so inclined, as to offer but little resistance to the motion of the stop-rim in either direction.

Other views of this spring are shown in Figures 2 and 3; and another form and arrangement are shown in Figures 4 and 5, where the spring L, instead of being fastened to the stop-rim, is secured to the handle D, and instead of striking into a notch, catches over a slight projection, d', upon the stop-rim B.

Fig. 4 represents a side view, and fig. 5, a top view of this arrangement.

The object of this improvement is to allow the machine to be started at any time when one of the tension-weights has fallen from a broken thread, without rendering the stop-motion liable to be caught, so as to prevent such starting.

Upon the spindle G, fig. 2, I place the flier H and spool P, so that both may turn together; but instead of the flier, an upright cylinder, furnished with a suit-

able number of vertical ribs, as shown in Figures 9 and 10, may be used.

Upon the tension-weight I, is placed the rib, or spur i, which, by engaging with the upright arms of the flier, or ribs of the cylinder, keeps the spool from turning, until the weight is so raised as to clear the top of the arms, or ribs h h, when the spool will turn, and the tension-weight fall, until it engages with the opposite, or adjoining arm, or rib.

In connection with the flier, or cylinder, I use a spring, operating upon the thread, so as to reduce the motion imparted to the tension-weight, as the carrier passes from the inner to the outer grooves of the machine.

This spring may be in any form, and must be placed between the tension-weight and the point where the braid is formed, and may be located at any point that shall be most convenient or desirable.

The operation of this spring is illustrated upon carriers 1 and 2, of fig. 2, where S is a guide-wire, encircled by a spiral spring, K, and provided with an eye, or any fixed point, n, for the passage of the thread.

In carrier 1, of fig. 2, the spiral spring is connected to a sliding thimble, Q, to which is attached a hardened-steel hook, or eye, m.

This sliding thimble is, preferably, made of wood, hard rubber, or sheet-metal, and may, by extending within the coils of the spring, be made to support the same.

Or this thimble may extend outside of the spring, as shown in Figures 11 and 12, and will thus tend to prevent the dust or lint from collecting within the coils of the spring.

In fig. 11, the spring K is contained between the stationary collar R and sliding thimble Q, so that a pull upon the thread will compress the spring; but in fig. 12, the collar R is fastened to the guide-wire below the sliding thimble Q, so that a pull upon the thread will extend the spring.

The arrangement shown in carrier 2, of fig. 2, is somewhat similar to that shown in fig. 11, the spring K being compressed between the stationary collar R and sliding thimble Q, the hook m being held, by passing loosely through a hole in the collar R.

In threading the carrier, the sliding thimble Q is raised by the thumb and finger, until the hook m rises through and above the eye n, when the thread can be readily caught under the hook. Now by releasing the thimble, it will fly back, through the action of the spring, carrying the bight of the thread with it through the eye n.

Other forms and arrangements of the spring K, op-

erating upon a bight of the thread, may be used in combination with a tension-weight, I, and a flier, or cylinder, with upright arms, or ribs *h h*. The forms shown, however, sufficiently exemplify the principle contemplated.

What I claim as my invention, and desire to secure by Letters Patent, is—

The combination of a handle, D, stop-rim B, spring L, and spring C, operating substantially as described.

Also, the combination of the spool P, revolving upright arms, or ribs *h h*, tension-weight I, and a spring, K, operating substantially as described.

Also, the combination of a tension-weight, I, spring K, sliding thimble Q, and guide-wire S, arranged upon a carrier, substantially as described.

Also, the combination of a spring, K, sliding thimble Q, stationary collar R, guide-wire S, and tension-weight I, arranged upon a carrier, substantially as described.

SOCRATES SCHOLFIELD.
